UNITED STATES PATENT OFFICE.

HERBERT O. RUSSELL, OF DETROIT, MICHIGAN, AND CHARLES LEIGH PAULUS, OF DAYTON, OHIO.

SIGNAL GUN.

Application filed April 18, 1922. Serial No. 555,407.

To all whom it may concern:

Be it known that we, HERBERT O. RUSSELL and CHARLES LEIGH PAULUS, citizens of the United States, residing, respectively, at Detroit and Dayton, in the counties of Wayne

and Montgomery and States of Michigan and Ohio, have invented certain new and useful Improvements in Signal Guns, of which the following is a specification.

This invention relates to a signal gun, the object in view being to provide a signal gun intended to replace the present Very pistol. Heretofore, in signaling from an aircraft, it has been the practice to aim the pistol out over the side of the ship in the act of firing a signal light. Due to the terrific blast of air it has been difficult to fire a pistol with one hand. Also when the spring of the Very pistol becomes weakened from long use the pistol is apt to miss fire, with a consequent danger to the ship, since accidental discharge is apt to occur after a misfire and before the defective cartridge can be ejected overboard. The signal gun of this invention is intended to be mounted inside of the cockpit, with its muzzle extending thru a hole in the floor, or the side of the ship, wherever it is considered advisable.

With the above and other objects in view, the invention consists in the novel construction, combination and arrangement herein fully described, illustrated and claimed.

In the accompanying drawings:

Figure 1, is a diametrical section thru the signal gun.

Figure 2, is a top plan view thereof, partially in section.

Figure 3, is a view in elevation of the gun.

Referring to the drawings, (1) designates the barrel of the gun, which is shown provided with lugs to enable the same to be mounted on an aircraft. (3) designates the breech block of the gun, which is connected to and displaceable with an L-shaped frame (4), having a portion which extends along one side of the barrel and is connected thereto by a pivot (5).

The gun is adapted to be fired by striking the hand upon a knob (6) which is attached to the firing pin (7), having a striker (8)

which operates through a hole (9) in the breech block. The knob and firing pin are upheld by means of an extension spring (10) which surrounds the pin (7) as shown in Figure 1.

The pin (7) is slidable in a tubular guide (11) which is formed in one piece with a latch lever (12) having at the free end thereof a locking lip (13) adapted to engage a corresponding lip (14) on the gun. By pushing the knob (6) laterally, in a direction away from the locking lips (13) and (14), the breech of the gun may be thrown open to insert a new charge or cartridge, the old shell being automatically thrown out by an ejector (15) which is thrust upwardly by an extension lip (16), on the lower end of part 4 of the breech block.

It will be observed from the foregoing description taken in connection with the drawings, that until the breech block is actually locked in its final firing position, the gun cannot be fired, because the striker will hit the side of the hole (9). The gun may be loaded, fired and unloaded—or the empty shell ejected by the use of one hand only.

Having thus described our invention, we claim:

1. In a signal gun, a gun barrel, a movable breech block, a breech block locking lever carried by the breech block, and a firing pin carried by said lever and movable therewith into and out of firing position.

2. In a signal gun, a gun barrel, a movable breech block, a breech block locking lever carried by the breech block, and a firing pin carried by said lever and movable therewith into and out of firing position, and a knob on said pin adapted to be struck by hand.

3. In a signal gun, a gun barrel, a movable breech block, a breech block locking lever carried by the breech block, yieldable means for holding said lever in locked position, and a firing pin carried by said lever and movable therewith into and out of firing position.

4. In a signal gun, a gun barrel, a movable breech block having an arm extending along the side of the barrel and pivotally at-

tached thereto, a breech block locking lever carried by the breech block, and a firing pin carried by said lever and movable therewith into and out of firing position. 10

5. In a signal gun, a gun barrel, a movable breech block, a breech block locking lever carried by the breech block, and a firing pin

carried by said lever and movable therewith into and out of firing position, and means for extracting the cartridge shell when the breech block is displaced.

HERBERT O. RUSSELL.
CHARLES LEIGH PAULUS.
